(57) **CLAIM**

The ornamental design for a charging connector for electric vehicle, as shown and described.

DESCRIPTION

FIG. 1 is a perspective view from the upper side of a charging connector for electric vehicle showing our new design;
FIG. 2 is a perspective view from the lower side thereof;
FIG. 3 is a front elevation view thereof;
FIG. 4 is a rear elevation view thereof;
FIG. 5 is a top plan view thereof;
FIG. 6 is a bottom plan view thereof;
FIG. 7 is a right side elevation view thereof; and,
FIG. 8 is a left side elevation view thereof.
The portions of the article shown in broken lines are for the purpose of showing environmental structure only and form no part of the claimed design.
